UNITED STATES PATENT OFFICE.

MELVILLE E. PETERS, GEORGE H. FATH, AND ALBERT F. MILLER, OF DENVER,
COLORADO.

GUMMED-BLANK AND UNWRAPPED-BOX REGISTERING MECHANISM.

1,229,510.

Specification of Letters Patent. Patented June 12, 1917.

Application filed February 8, 1916. Serial No. 76,992.

To all whom it may concern:

Be it known that we, MELVILLE E. PETERS, GEORGE H. FATH, and ALBERT F. MILLER, citizens of the United States of America, residing in the city and county of Denver and State of Colorado, have invented a new and useful Gummed-Blank and Unwrapped-Box Registering Mechanism, of which the following is a specification.

Our invention relates to a gummed blank and an unwrapped box registering mechanism for blank and label gumming machines, in which means is provided for gluing the bottoms of paste-board boxes of either the stayed corner type, the unstayed corner type, or the extension edge type of unwrapped or uncovered paste-board boxes directly to the gummed surfaces of the blanks, as they are gummed in a gumming machine and are conveyed away from it after being coated with any adhesive gum or glue; and the objects of our invention are:

First, to provide means for gluing boxes directly to gummed blanks as they feed from the gumming mechanism.

Second, to provide means for conveying the gummed blanks to a predetermined point by a suitable conveyer and then picking them off of the conveyer and feeding them forward to the top of a suitable table, which is arranged to permit the box to be glued directly to the gummed blank. And

Third, to provide a rapidly operating direct manner of adhesively attaching the bottoms of paste-board boxes to finishing blanks or labels, that enables the boxes to be accurately centered on their covering or wrapping blank or labels at the time and in the same machine they are freshly gummed in, and as they feed in one continuously feeding movement through the gumming machine.

We attain these objects by the mechanism illustrated in the accompanying drawings, in which:

Figure 1 is a plan view of the improved gummed-blank and an unwrapped box registering mechanism for blank and label gumming machines.

Fig. 2 is a side elevation thereof.

Fig. 3 is a vertical, longitudinal sectional view of the same.

Fig. 4 is a vertical transverse sectional view through one side of the frame, showing the mechanism for raising the blank gripping suction tubes and for moving them forward and backward.

Fig. 5 is a top view of the bar for raising suction tubes and showing the slide bar on which the cross head which supports the tubes is slidably mounted.

Fig. 6 is a vertical sectional view through one of the suction tubes, its supporting hub, and the air supply tube upon which the hubs are mounted.

Fig. 7 is an end view of the cross bar which carries the spring actuated blank grippers.

Fig. 8 is a rear view of one end of the bar shown in Fig. 7, and illustrating more clearly the spring actuated pawl and ratchet mechanism by which the gripper bar is held in an inoperative position.

Fig. 9 is a vertical sectional view through the gripper carrying bar, and one of the grippers and its supporting block.

Fig. 10 is a sectional view, showing the mechanism for throwing back the grippers to release the blanks. And

Fig. 11 is a rear view on a reduced scale of a portion of the machine, showing the operating cams and levers actuated thereby.

Similar letters of reference refer to similar parts throughout the several views.

Referring to drawings,—

The numeral 1 designates a fragment of the supporting frame of our invention. The fragment of the frame illustrated is the rear or discharging end of the frame of the gumming machine. This frame consists of two side frames 2 and 2^A, spaced at sufficient distances apart to receive most of the machine's mechanism between them. These side frames 2 and 2^A rest on and are secured to a base plate 3, and a cross brace bar 4 is extended between these frames and extends through and is bolted to them to rigidly secure them together. The rear end of each frame is provided with a rearwardly extending arm 5, that supports a cross bar 6 that extends from one side frame to the other. This cross bar is provided with longitudinal slots in which sliding clips 7 are fitted that are adjustably clamped in the slots and to the

cross bar by cap screws 8. These sliding clips 7 are provided with rearward extensions 9 that are adapted to form box end positioning and guiding clips, and they are positioned at equal distances from the longitudinal center line of the machine, and are set at a distance apart to receive the ends of the size of boxes it is desired to attach to the blanks being run through the gumming machine and gummed. The blanks are fed to the gumming mechanism and then to a conveying mechanism; we do not however illustrate the blank feeding and gumming mechanism, but we illustrate only the discharging end of the endless blank conveyer transmission mechanism. A side box guiding clip 10 is secured to the center of the cross bar. These three box guiding clips are curved rearwardly at their upper ends, so that the boxes can be quickly placed between them without striking their upper edges.

The machine and its gumming mechanism, as well of the blank receiving end of the conveyer, are fully illustrated in our pending application Serial Number 30,471, filed May 25, 1915, for a pneumatically controlled and automatically operating blank gumming and tempering machine.

In that pending application the blanks are fed to a blank feeding roller, and this feed roller feeds them to a gumming cylinder, from which they are transferred to an endless conveyer, the end of which that lies adjacent to the gumming cylinder is supported by sprocket wheels, and the center of the conveyer which is provided with blank supporting aprons runs over a gapped cylinder which we term a transmission cylinder. This conveyer has an intermittent movement and it stops long enough at its reverse turning point, which is marked by an arrow which point we call its stopping or discharging station. We do not illustrate the mechanism that intermittently starts, runs and stops this endless conveyer, as it is controlled by the rotary movement of the gumming cylinder, and is illustrated in the above mentioned application.

Each blank supporting apron of this conveyer is provided with a plurality of blank gripping fingers, which enters the gap of the transmission cylinder as the aprons rotate and they are positioned to grip each blank by its forwardly feeding edge as it is coated with gum by the gumming cylinder, and peel it off from the gumming cylinder onto its adjacent apron against the top surface of which the blank feeds out flat or as the apron turns up over the peripheral surface of the transmission cylinder.

The aprons with the blanks on them travel in a straight horizontal plane from the top of the transmission cylinder to its stopping station, from which point it runs over

sprocket wheels 12 and a roller 14 and then down and back to an idler supporting member and then up to the transmission cylinder.

The above brief description is all that is deemed necessary of the blank feeding gumming and the blank receiving end of the endless apron conveyer that delivers the blanks to the air gripping tubes of our box and blank registering mechanism.

Our present invention does not appertain to the blank feeding or gumming mechanism. Consequently we deem it sufficient to say that the blanks are properly gummed and are fed onto the conveyer, and are delivered to apparatus which we will presently describe that transmits them one at a time onto a table where an attendant can place a box directly and centrally on top of and against the gummed surface of the blank. Instantly afterward the blank with the box adhesively fastened to it, is fed into engaging relation to the upper plunger of a box wrapping machine. The conveyer consists of the oppositely arranged side chains 11, which are mounted on sprocket wheels 12 that are secured on the opposite ends of a shaft 13, on which a roller 14 is mounted and secured.

A bar 15 is placed across and between the sprocket chains, the opposite ends of which are secured to the sides of the links they are placed between.

This bar 15 forms the advance feeding end, which is the end that is traveling forward to convey the blanks from their gumming mechanism to the discharging end and stopping station of the conveyer and of the blank supporting aprons 16. These aprons are preferably made of rubberized cloth but may be made of any other suitable material. They are made wide enough and long enough to support on their top surface the largest size blanks the gumming machine will apply a coat of adhesive gum or glue to. Their advancing edge is secured to the bar 15 by a clamping strip 17, that is seated in a stepped recess 18, that is preferably inclined downwardly and forwardly from the top surface of the bar. The clamping strip is secured to the bar by flush headed screws 19, which when loosened permit the edge of the apron to be tucked under it. The edge of the apron is then clamped by the screws and strip against the inclined stepped portion of the bar. The opposite end of each apron is secured to a bar 20, that extends across and between the sprocket chains of the conveyer, and is secured to the links of the chain it is placed against. There are a number of ways of securing the rear end of each apron to its supporting cross bar, but we preferably lace this end of the apron to these cross bars by a lacing 21, which is laced through suitably formed apertures formed both through the edge of the apron and through the bars.

The lacing permits the apron to be stretched tightly between its supporting bars, and to be tightened and adjusted from time to time as it stretches. There are preferably nine of these aprons in the length of this endless conveyer, and they are spaced at a distance apart that will allow them to receive the blanks from the blank gumming cylinder of the machine.

- 10 The top of the bar 15 is provided at intervals across its length with thin disks 22, which are provided with stem portions 23 that are inserted in the top of the bar so that the disks rest flat against the top of the bar.
- 15 These disks make raised flat round points for the advancing or forwardly moving blanks to rest on, as will be presently described.

Two rows of these disks are provided, one row being offset slightly to one side of the other, and the disks of one row are preferably set close to the disks of the other row, and both rows are of the same height.

The top of each disk in one of the rows of disks is engaged by a finger gripper 24, which grippers are arranged to grip and clamp the edges of each blank to them, a row of which is provided, as will be presently explained, while the top of each disk 25 in the row of disks is engaged by an air suction tube 26, a row of which is provided, as will be presently explained.

Each gripping finger in the row of blank gripping fingers is pivotally mounted in a block 27 which is mounted on a square bar 28 that is mounted at its opposite ends in lugs 29, that project from the blank gripping side of the cross bar 15. The blocks 27 on this blank gripping finger supporting bar are provided with recesses in which a lug 30 portion 30 of each finger is placed. The bottoms of each of these recesses are beveled downwardly from the top surfaces, and a pin 31 is extended entirely through the block and loosely through the lugs of the blank grippers. Each blank gripper comprises a central body portion, from the bottom of which the lug depends. This central body portion extends into a blank gripping finger portion 24 that terminates in a flat end on its under side that engages and rests on top of its adjacent disk. This central body portion also extends in an opposite direction from the blank gripping finger and terminates in an end on the under side of which engages the top end of an expansive coiled spring 32 that is seated in a hole 33 formed in block 27 on the bar 28 to receive it. This expansive spring 32 has a tendency to normally hold the end 34 of the finger up, and the end 35 of the finger down with a resilient tension against the top of its respective disk. Consequently when they are moved to grip a blank against the disks 22 they do so with a backwardly yielding resilient pressure. The bar itself

to which these blank gripping clips are pivotally connected extends rotatively through its lugs at both ends, and at one end beyond the lug a disk 36 is secured on it, and secures this bar against lateral movement in its lugs. The peripheral edge of this disk 36 is provided with a ratchet toothed lug 38 which is adapted to be engaged by a pawl 39 when the blank gripping fingers are raised to release each blank at the blank releasing and the stopping station of the conveyer, as will be presently explained.

This pawl is a rock arm pawl and it is pivotally attached to a projecting portion 40 of the bar 15, by a pin 41 that projects beyond the projection far enough to receive a coiled spring 42, one end of which is attached to the lug 40 and its opposite end is secured to a collar 43 secured on the pin. This spring is arranged to hold the toothed end of the pawl with a resilient pressure against the peripheral surface of the disk, while the tooth 43 of the pawl is arranged to engage the tooth of the disk when the disk is turned far enough around by the upward and backward movement of the fingers.

The bar 28 is provided on its opposite end portions inside of its supporting lugs with reduced portions, on each of which a coiled expansive spring 44 is mounted; one end of each of these springs projects into apertures in the lugs and is thus secured to them, while the opposite end of each spring is secured to a collar 45, that is loosely mounted on the reduced portion of the bar. Each of these collars is provided at four diametrically opposite points with slots, and a pin 46 is secured to each of the reduced portions of the shaft adjacent to the slotted end of its collar and the slots in the collars fit loosely around its adjacent pin, which becomes a tightening and locking pin for the collar.

The expansive tension of the spring holds the collars when one of their slots surrounds the pin against it by a longitudinal thrust, while the pin locks the collar and spring against a turning movement.

These springs are adapted to exert a downwardly turning throw movement on the bar and a yielding pressure relief movement to the fingers when they are released from the pawl, which is accomplished by a cam, at that point of the conveyer's traveling movement which is at the blank gumming and transmission cylinders of the machine.

The gumming and the blank transferring mechanism that operate to grip each blank as it is coated with gum, onto the transmission cylinder and the aprons of the endless conveyer, we do not illustrate in this application, but they are fully illustrated and described in our above mentioned pending application.

These blank gripping fingers are automatically raised to release a blank by a segment gear 47 that is arranged and operated as follows:

- 5 On the opposite end of the finger engaging bar from the ratchet toothed disk, a segment toothed pinion 48 is secured that contains gear teeth on its periphery, and these teeth as the conveyer chain comes to a stop,
- 10 are in position to be engaged by the teeth 49 of the toothed segment lever 47 that lies in the traveling path of the segment toothed pinion 48 of the bar 28. This segment toothed lever is mounted on the shaft 13
- 15 that supports the conveyer's sprocket wheels, and its roller, on which the conveyer turns. This segment toothed lever is pivotally connected to one end of a link 50, the opposite end of which is pivotally secured to one end 20 of a bell crank lever 51, the other end of which is attached to a connecting rod 52, the opposite end of which is pivotally connected to one end of a rock arm 53, which is pivotally attached intermediate of its end 25 to the frame of the machine. The opposite free end of this rock arm is provided with a roller 54 that projects into a cam runway track that is formed in one side of a disk 55, that is mounted on a shaft 56.
- 30 This segment toothed pinion is engaged by the segment tooth lever just after the bar with the fingers gripping a blank to it, reaches the stopping station of the conveyer, and the cam actuated levers pull the segment toothed lever to rotate the segment pinion just after the tubes 26 have engaged the edge of the blank.
- 35

This partial rotating movement that the segment lever imparts to the segment pinion, 40 turns the blank gripping finger bar in a direction that swings the blank gripping finger upward and backward far enough to instantly release the gummed blank, as it lies on its apron, and instantly before these 45 fingers are raised up the air inlet suction tubes 26 are moved down on top of and against the blank and the disks upon which the advance edge of the blank still rests, and these tubes bear against the blank and disk 50 which insures that each tube will have a firm bearing against the blank.

The top of the disks acts as an abutment to the yielding pressure of the tubes. Then 55 instantly after the tubes bear firmly against the disks the suction force acting in the tubes 26 causes the tubes to grip by suction the blank; the tubes then lift the blank off from the conveyer apron 16 and move it forwardly a short distance and deposit it on 60 a reciprocating table 57, which instantly grips the blank by air suction. The table then carries the blank forward under the box guiding clips 9 and 10, and then stops long enough for an attendant to place a 65 box directly on and press it down firmly

and evenly against the gum coated central body portion of the blank, which adhesively sticks and secures the blank to the bottom of the box. Then instantly after the attendant lifts the box within the blank firmly 70 glued to it off from the table and transfers it by hand to the upper plunger of a box wrapping machine, which we do not illustrate.

Our preferred construction of the mechanism that accomplishes these functions is as follows, although our invention contemplates any and every and all means by which they can be accomplished:

To the side frame 2 of the machine, a vertically reciprocating bar 58 is slidably mounted in guideways 59 and 60 that are formed on the side frame. This frame is reciprocated by a cam groove 61, that is engaged by a roller 62. This roller is pivotally mounted on a laterally projecting lug portion that is formed on the lower end of the bar. This vertically reciprocating bar extends above the side frame 2, and at its upper end it is provided with a cross bar 63, which forms a slideway. A cross head 64 is slidably mounted on the slideway of the cross bar. This cross head is provided with a laterally extending hub 65, that extends at right angles to the longitudinal axis 65 of the machine and toward the opposite side frame 2A, and a tubular bar 66 extends into it and is rigidly secured to it. This tubular shaft has an axial aperture that extends from its inner end to near its opposite end. 100 Both ends however are plugged up and an air inlet aperture is made through the hub 65, and through the tubular shaft, into it. This tubular shaft extends over the roller 105 on which the aprons of the conveyer turn, and they are positioned to move vertically and reciprocally above and toward it a distance sufficient to allow its air suction tubes to grip and lift the blanks and carry them above and deposit them on the table 57. 110 Each of these blank suction gripping tubes is mounted on the tubular shaft and has a slight turning movement thereon that gives each tube a pressure relief movement independent of the others. We preferably illustrate six of these air suction tubes, although 115 a more or less number of them may be used if desired.

Each of these air suction tubes comprises a tube holding stem 67 that is provided with a hub 68 which is loosely mounted on the tubular shaft, and is held thereon by a pin which extends loosely through an aperture in the hub to receive it, which aperture is made enough larger in diameter than the 125 pin to allow the hub and its stem a turning movement on the tubular shaft of about an eighth of an inch. The stem 67 is provided with a rearwardly extending lug portion 69 through which a screw 70 is threaded to 130

stand vertically. A horizontal screw 71 passes through a slot in the hub 68, and is screwed into the tube 66, and a coiled expansive tension spring 72 is mounted on the pin 5 at one end and bears at its opposite end against the outer end of the screw 71. The top end of the screw is provided with a screw driver slot to enable it to be turned to adjust the pin 70, which carries a washer 10 7^A that bears upon the top of the spring, so that the tension of the spring may be varied. A nut 72^A is also threaded to the screw and is turned against the top of the lug to lock it in adjusted positions. Each 15 tube holding stem is provided with a vertical lug member at its outer end that is provided with a vertical aperture in which the tubular member 26 is slidably mounted. These tubular members we term the air suction tubes, and they are each adjustably secured in its respective vertical slideway by a set screw 73. Each of these air suction tubes is provided with an axial bore 74 that extends into its lower end to near its top 20 end, and an aperture 75 is formed through its side. The stem 67 is also provided with an axial aperture 76 that registers at one end with the side aperture in the tubular member 26, and at its opposite end with an aperture 77 that is formed through the adjacent side of the tubular shaft into its axial aperture 78. The upper end of each air suction tube is provided with a knurled surface that enables the tube to be easily held by the 25 fingers of an attendant. As the air inlet ends of these air suction tubes are constantly engaging the gummed surfaces of the blanks, they are each slightly coated with gum when they release a blank on the table, and it is necessary that some means be employed to 30 wipe or wash their ends in order to wash off from them any moist gum that may be on them. There are a number of ways in which this feature of our invention can be carried out. We preferably however construct 35 and arrange this feature of our invention in the following manner, although our invention contemplates all means by which the ends of the air suction tubes of our invention can be cleaned after depositing each blank on its box applying table and before picking up another blank from the 40 conveyor.

Across the machine from one side to the other, and at right angles to the longitudinal axis of the machine, we mount in bearings a shaft 79 to which an oscillating rocking motion is imparted by a cam actuated lever mechanism, which consists of a lever 45 80 that is secured to one end of the shaft, to the outer end of which a connecting lever 81 is pivotally secured, the opposite end of which is pivotally connected to one end of a rock arm 82, which is pivotally connected 50 to one end of a spindle 82^A. The opposite

end of this spindle carries a rock arm which is provided with a roller 83, that projects into an inclosed runway cam which is formed on one side of a disk 84 that is mounted on the shaft 56 that is driven by 55 any suitable rotary power transmitting means from the main driving shaft, which power transmission means we do not illustrate.

Upon the oscillating movement shaft 79 we mount and secure a plurality of arms 85, the number being the same as the number of air suction inlet tubes 26 on the tubular shaft, and each arm is secured on the oscillating shaft opposite to one of the air 60 suction tubes. Each of the arms is provided with a roller 89 at its free end, which is positioned in alignment with and in the path of the rearwardly moving air inlet suction tubes at the upper end portion of their reciprocal swinging oscillating stroke movement. Directly below these arms and in their swinging movement path, a pan 86 is secured to a bar 87, which is secured to the frame work of the machine by screws 88. 65 This pan is provided with a supply of water to a sufficient depth to fully immerse the roller 89, of the arms at the end of its downward stroke movement. Consequently the rollers which are arranged in alignment 70 across the shaft 79, are all dipped into the water as each blank is fed forward onto the table 57 and their rollers are swung up by their actuating cams into the path of the blank engaging ends of the rearwardly moving air suction inlet tubes, which the ends of the tubes strike and rub against as they move past the rollers, which are free to turn slightly under the pressure of the moving tubes which can yield upwardly slightly 75 to pass over the rollers with an adjusted frictional pressure against the surface of the rollers that will effectually wash and clean and wipe the blank engaging ends of the air inlet suction tubes. The air suction tubes 80 and their supporting cross head are reciprocated in a horizontal plane in connection with their joint raising and lowering movement by the arm actuated cam and lever mechanism, by a train of gearing, which is actuated by a cam actuated lever mechanism, and this cross head and air suction inlet tube reciprocating mechanism comprises the following instrumentalities:

Upon the back of the reciprocating cross head a toothed rack 90 is secured in which a pinion 91 meshes. This pinion is mounted on one end of a vertical shaft 92, and as this pinion is rotated in reverse directions it reciprocates the cross head in opposite 120 directions on the bar 63. The opposite end of the shaft 92 extends to near the base plate 3 of the machine, and its lower portion is square in cross section and passes 125 slidably through a corresponding aperture 130.

in a pinion 93, which is rotatably mounted in suitable bearings 94, secured to the adjacent side frame. The pinion 93 meshes with a toothed rack portion that is formed on one end of a bar 95 that is reciprocally mounted in suitable bearings 96 that are secured to the frame work of the machine. The opposite end of this bar is also provided with a toothed rack portion 97 that meshes with a pinion 98 that is mounted on one end of a stub shaft 99 that is rigidly mounted in a suitable bearing 100 that is secured to the bed plate 3. A gear 101 is secured on the hub of the gear 98, and this gear meshes with a toothed rack portion 102 that is formed on one end of a rack bar 103 which is slidably mounted in a suitable bearing 104 that forms part of the bearing 100. The opposite end of this rack bar is pivotally connected to one end of a link 105, the opposite end of which is pivotally connected to one end of a lever 106, the opposite end of which is pivotally secured to a shaft 107 which is supported in the frame of the machine. A roller 108 is pivotally secured to this lever intermediate of its ends, which projects into an inclosed cam runway track that is formed on one side of a cam disk 109 that is mounted on the shaft 56, which reciprocates the lever 106 and the lever through the medium of the link 105 reciprocates the rack bar 103 which rotates the gears 101 and 98 and the gear 98 drives the rack bar 95 which rotates the vertical shaft 92 and its upper pinion reciprocates the cross head and the air suction tubes, from the stopping station of the conveyer, where they pick up a blank to the top of the table 57, where they deposit it, as will be presently described.

The blank receiving table consists of a rectangular shaped flat piece of any suitable material, preferably aluminum, which is secured at its opposite sides to tooth rack bars 110, that are reciprocally mounted in suitable guideways 111, that are formed in bars 112 that are secured to the opposite side frames of the machines. The gear teeth of these rack bars 110 are engaged by two gears 113 that are secured on the opposite end portions of a shaft 114 that extends transversely across the machine and is rotatably journaled in bearings formed on the side frames. A pinion 115 is also secured on this shaft which is engaged by the gear teeth of a vertically positioned rack bar 116 which is reciprocally mounted in bearings 117 that are secured to the adjacent side frame. The lower end of this reciprocating bar is provided with a block 118 that is slidably and adjustably bolted by a bolt in a slot 119 that is formed in the bar, through which the bolt passes. The block 118 is pivotally secured to one end of the bar 120 and to the other end of this bar one

end of a lever 121 is pivotally secured. The opposite end of this lever is rigidly connected to a short shaft 122 which is pivotally mounted in the frame, and a lever is secured upon the opposite end of the shaft 122 to which a roller 123 is pivotally secured and is arranged to extend into an inclosed cam runway track that is formed on one of the sides of the cam 84, which is secured on the shaft 56. The cam as it rotates causes the lever to reciprocate the vertical rack bar, which causes the pinion 115 to rotate the shaft 114 and its gears 113, and the gears 113 to reciprocally move the table supporting rack bars 110 and consequently 80 the table. As illustrated, the table is at the end of the outer stroke of its reciprocal movement, and the air suction inlet tubes on the backward stroke of their reciprocal movement have traveled to a point where 85 they engage their wiper rollers. When in operation, these air suction tubes move back to a position centrally above the roller 14 and when in that position the rear edge of the table moves back to the dotted line A. 90 The air suction tubes receive the air suction force from an air pump 124 that is mounted on the base plate of the machine, and this pump is operatively connected by a hose to an air inlet aperture that is formed in the 95 hub 65 of the cross head that connects with the axial aperture of the tubular shaft 66. The air pump's piston rod is pivotally connected at its outer end to one end of a lever 125, the opposite end of which is pivotally mounted on the shaft 107 and this lever is provided with a roller intermediate of its ends that projects into an inclosed cam runway track that is formed on one side of the disk 109 that is mounted 100 on the shaft 56. The rotary movement of the cam reciprocates the piston of the air pump, which is timed to create an air suction drawing force in the entrances of all of the air inlet tubes simultaneously, thus 110 causing them to suck and draw to them that portion of the blank each tube bears against, and this suction drawing force is strong enough to cause the tubes to grip each blank tight enough to lift it up from the conveyer 115 when the tubes are moved vertically upward, and to hold it while they are moved forwardly over the table, and to release it by the reverse movement of the piston, which breaks the suction force instantly after the 120 tubes have moved down and presses the blank down against the surface of the table against which the tubes rest so as to press the blank down firmly and tightly against the air suction inlet apertures of the advancing edge of the table, which are positioned transversely along the advancing edge of the table close to and in alignment with and between the points on the table 125 the tubes move down and rest on and hold 130

the blank against. The table's blank gripping air inlet apertures 126 extend through the top surface of the table into a hollow box-like chambered portion 127 that is formed on the under side of the table, to which one end of a hose 128 is connected, that connects to a cam and lever actuated air pump which we do not illustrate, as it is of the same construction and arrangement as the air pump and its cam and lever actuated mechanism that produces the air suction blank gripping force of the air inlet blank gripper tubes.

When the table has gripped a blank and fed it forward to the limit of the forward stroke of its reciprocal movement, it stops for a few seconds before it starts on the rearward stroke of its reciprocal movement, and an attendant places a box between the guides 9 and against the guide 10, which are positioned to allow the box to be placed centrally over the central body portion of the gummed side of the blank, when it is removed from the table and is placed by hand on the upper plunger of a box wrapping machine, of which there are a number in common use. An improved box wrapping machine that is especially adapted to be used to receive the boxes with their labels attached, is illustrated in our pending application Serial Number 59,860, filed November 5, 1915, for an automatically operating multiple stage box wrapping machine.

The operation of our blank and box registering mechanism for blank gumming machines, is as follows:

The blanks are fed on the aprons in a continuous and successive stream to the conveyer's stopping and blank discharging station, and then each blank is gripped at its advance edge portion, and is picked up by the air suction tubes 26 and is lifted up above the table and is carried forward by these tubes to the front edge of the table. The tubes then move down and place the edge of the blank directly over the air suction inlet apertures of the table, and press its edge against them and instantly after the table's air suction inlet apertures grip the blank the tubes release it while the table holds it and the body of the blank lies flat on the table. The table then moves forward under the box guiding clips and stops there for a few seconds, and the instant it stops the attendant quickly places a box between the guide clips and presses it down evenly and firmly against gummed surface of the central body portion of the blank, and then instantly removes the box from the table. The box has the blank adhesively sticking to it, and the attendant then takes it and places it on the upper plunger of a box wrapping machine, which should be positioned close enough to the gumming machine for the attendant to make this transfer quick enough to be ready

to place a box on the next blank that is fed out by the table in box receiving position, as instantly after the box and blank are removed from the registering table, the table is moved back in position to receive another blank from the air suction blank lifting and forwardly feeding tubes.

The various mechanisms are adapted to be changed to fit boxes of all sizes, ranging from about 2x4 to 12x20 inches in size and of varying depths.

Having described our invention, what we claim as new and desire to secure by Letters Patent, is:

1. Gummed blank and box registering mechanism, comprising the combination of gummed blank conveying mechanism, with a table arranged to receive and hold the blank in a predetermined position, means for guiding a box centrally against the gummed side of the blank, comprising a gummed blank conveying mechanism, a table arranged to receive the blanks from said conveyer mechanism, and a plurality of air suction air inlet apertures in said table connected to operative air suction force producing mechanism for holding said blanks on said table in a predetermined position.

2. Gummed blank and box registering mechanism, comprising the combination of gummed blank conveying mechanism, with a table arranged to receive and hold the blank in a predetermined position, means for guiding a box centrally against the gummed side of the blank, a table arranged to receive the blanks from said conveyer mechanism, a plurality of air suction air inlet apertures in said table connected to operative air suction force producing mechanism for holding said blanks on said table in a predetermined position, and adjustable box end and side engaging clips arranged over said table to guide the boxes centrally onto the blanks on said table.

3. Gummed blank and box registering mechanism, comprising the combination of a gummed blank conveying mechanism, with a table arranged to receive and hold the blank in a predetermined position, means for guiding a box centrally against the gummed side of the blank, a table arranged to receive the blanks from said conveyer mechanism, a plurality of air suction air inlet apertures in said table connected to operative air suction force producing mechanism for holding said blanks on said table in a predetermined position, and adjustable box end and side engaging clips arranged over said table to guide the boxes centrally onto the blanks on said table.

4. In a gummed blank and unwrapped box registering table, the combination with the conveyer, said conveyer being provided with blank gripping and holding means and with a stopping station, said conveyer being

provided with a blank releasing mechanism at its stopping station, of a plurality of air suction blank gripping tubes arranged to engage said conveyer at its stopping station 5 and grip and raise a blank therefrom, a table reciprocally mounted adjacent to said blank gripping and lifting tubes, means for reciprocally moving said tubes over said table, means for lowering said tubes to deposit the blank on said table in a predetermined position, means including an air suction force connected with said table for gripping the blanks as they are deposited on its surface by said air suction tubes, and 10 means including box guiding clips for placing a box centrally on the blank on said table, whereby said box is adhesively glued to said blank.

5. The combination of the gummed blank 20 conveyer with a reciprocating table adapted to receive the gummed blanks in a predetermined position, means including adjustable guides for manually guiding a box against a blank on said table, and means including a 25 plurality of air suction operating tubes for gripping the blanks on the conveyer and transmitting them to their predetermined position on said table.

6. In a gummed blank and box registering 30 mechanism, the combination of the endless intermittent movement conveyer, the air suction blank gripping tubes arranged to grip a blank on the conveyer, the air suction blank gripping table, the cam actuated 35 means for causing said air suction blank gripping tubes to grip and convey the blanks to the table and the adjustable box guiding clips arranged to allow an attendant to place a box centrally on and press it against 40 and adhesively glue it to the blank while held on the table.

7. In a gummed blank and box registering 45 mechanism, the combination with the conveyer, of the vertical and horizontal reciprocal movement, air suction blank gripping tubes each of which is provided with a resiliently yielding pressure blank engaging mechanism, means including a supporting 50 slideway for vertically adjusting each tube independent of the others, a blank receiving reciprocating table adjacent to said tubes

and means for imparting a combined vertical blank lifting, conveying and depositing movement to said tubes whereby they move down, engage, pick up and convey the blanks 55 one at a time over said table and to move down and deposit them at a predetermined point against the surface of said table, an operative air suction inlet blank gripping row of holes in said table arranged to register close to the table engaging ends of said tubes, and means including adjustable box guiding clips arranged to permit an attendant to guide and place and press a box 60 against the center of said gummed blank 65 while gripped by said table.

8. In a gummed blank and box registering mechanism, the combination of the reciprocating blank gripping air suction tubes, 70 with a tube end cleaning mechanism comprising a roller arranged in the rearwardly moving stroke of each tube, a liquid containing box below said roller and cam actuated means for dipping each roller in the liquid of said box, and moving them into wiping relation with the end of each tube whereby the blank engaging end of each tube is cleaned on the rearward stroke of each of its blank conveying movements.

9. In a gummed blank and box registering 80 mechanism, the combination of the reciprocating blank gripping and conveying tubes, with a wiper washing and cleaning mechanism adapted to wipe the blank engaging ends of each of said tubes after each blank 85 engaging movement, said wiper mechanism comprising a reciprocating roller for each tube, a water supplied box positioned in the downward path of the roller whereby it is covered with water at each downward 90 stroke, and cam actuated means including a lever mechanism arranged to lift said water covered rollers in the engaging path of said tube end's backward movement.

In testimony whereof we affix our signatures in presence of two witnesses.
